UNITED STATES PATENT OFFICE.

GEORGE KÜHN, OF ST. LOUIS, MISSOURI.

DESIGN FOR A HOUSING FOR SASH-PULLEYS.

SPECIFICATION forming part of Design No. 16,980, dated November 9, 1886.

Application filed October 1, 1886. Serial No. 215,109. Term of patent 14 years.

To all whom it may concern:

Be it known that I, GEORGE KÜHN, a citizen of the United States, residing at St. Louis, in the State of Missouri, have invented and produced a new and original Design for Sash-Pulleys, of which the following is a specification.

The nature of my design is illustrated in the accompanying drawing, being a perspective view of the sash-pulley, which consists of the housing A, face B, with circular perforations C C E E, and longitudinal slot D, also pulley F and pivot G, the perforations C C being parallel with each other and above the slot D.

I claim—

The within-described design, the same consisting of the housing A of a sash-pulley, having a face, B, perforated as described, and shown in and by the accompanying drawing. ²⁰

In testimony whereof I have signed my name to this specification in the presence of two subscribing witnesses.

GEORGE KÜHN.
